UNITED STATES PATENT OFFICE

ERICH WANNER, OF BASEL, SWITZERLAND, ASSIGNOR TO THE FIRM J. R. GEIGY S. A., OF BASEL, SWITZERLAND

PRODUCTION OF DYEING CONVERSION PRODUCTS OF AZO-DYESTUFFS

No Drawing. Application filed February 18, 1932, Serial No. 592,843, and in Germany February 28, 1931.

This invention is an improvement in or modification of the production of conversion products of azo-dyestuffs described in the specification of the U. S. Patent No. 1,850,875 dated March 22, 1932. In that specification there is described a process for the manufacture of dyeing products obtained by subjecting a monoazo dyestuff formed by coupling a diazotized amino sulphonic acid compound of the benzene and naphthalene series with resorcin to the action of an oxidizing agent, particularly to air, in presence of ammonia.

According to the present invention this process is conducted in such a way that a monoazo dyestuff formed by coupling a diazotized amino sulphonic acid compound of the benzene and naphthalene series with resorcin is subjected to air as oxidizing agent in presence of ammonia and of heavy metals, such as iron, copper and the like, or compounds thereof, singly or in admixture.

In this manner, dyeing conversion products are obtained which are still azo dyestuffs, but of which the exact constitution cannot be given. By this treatment, the original dyestuffs which yield mostly yellow to red dyeings become reddish- to violet-brown dyestuffs that are no longer capable of dyeing wool or silk or have only a little dyeing effect thereon, but which have taken an increased dyeing power on leather, the same being dyed in reddish- to violet-brown shades of very good fastness to light and alkaline fat liquor. By the additional use of a heavy metal, or a compound thereof, the duration of the conversion is favorably influenced as well as in some cases also the shade of the dyeings of the products.

The following examples illustrate the invention, the parts being by weight:—

Example 1

50 parts of the azo-dyestuff from diazotized 2-amino-1-hydroxybenzene-4-sulpho-6-carboxylic acid and resorcin are dissolved by heating in 500 parts of water with 50-60 parts of ammonia of 25 per cent strength and stirred at 85° C. for 8 hours whilst air is introduced by means of an iron tube. The

conversion product thus formed is then isolated by acidification with hydrochloric acid and precipitation with common salt and thereupon freed from adhering dissolved metal by washing with diluted hydrochloric acid.

The new dyestuff dyes leather of somewhat more yellow-brown tints than the dyestuff produced without the presence of metal, which in its turn requires about 16 hours in order to be thoroughly oxidized. If the heating of the solution and the maintenance of its temperature is performed by means of a steam supplied sinuous tube of iron, the duration of the reaction further diminishes to about 2-3 hours.

The dyestuff produced in this manner, but in presence of copper, dyes leather of somewhat more reddish-brown tints. The duration of the reaction, however, rises to about 8 hours when using a steam supplied sinuous tube of copper and to 10-12 hours when using a copper tube for the introduction of the oxidizing air.

Instead of the free metal, also metal salts, such as for example copper sulphate, ferro-sulphate, ferric chloride etc. can be used.

Example 2

The azo-dyestuff obtained from 31 parts of diazotized 4-nitro-4'-aminodiphenylamine-2-sulphonic acid and 12 parts of resorcin is dissolved in 500 parts of water, which has been rendered distinctly alkaline by means of ammonia, and subjected to oxidation by air at 95° C. for about 20 hours as described in Example 1. Thereupon the conversion product is worked up as hereinbefore described. To heat the solution and to maintain the temperature, steam serpentine of iron or copper are used; the tube serving for the introduction of air consists also of one of the said heavy metals.

Without the presence of metal, the complete conversion to the oxidized dyestuff requires at least 40 hours. The same constitutes a dark powder, is easily soluble in water and dyes leather of dark brown tints of excellent fastness to light and alkaline fat.

liquor. The tints may vary somewhat according to the kind of the used metal.

As azodyestuffs to be oxidized in presence of heavy metals there may also be used for example the dyestuffs from sulphanilic acid and resorcin, from 1.4-naphthylamino-sulphonic acid and resorcin, from 2.3.6-naphthylamino-disulphonic acid and resorcin, from aminoazobenzenedisulphonic acid and resorcin, from 2-nitro-4'-aminodiphenylamine-4-sulphonic acid and resorcin, and so on.

What I claim is:—

1. A process for the production of dyeing conversion products of azo-dyestuffs, consisting in subjecting a monoazo dyestuff formed by coupling a diazotized amino-sulphonic acid compound of the benzene and naphthalene series with resorcin to air as oxidizing agent in presence of ammonia and a heavy metal catalyser selected from the group consisting of iron and copper.
2. A process for the production of dyeing conversion products of azo-dyestuffs, consisting in subjecting a monoazo dyestuff formed by coupling a diazotized aminosulphonic acid compound of the benzene and naphthalene series with resorcin to air as oxidizing agent in presence of ammonia and copper.
3. A process for the production of dyeing conversion products of azo-dyestuffs, consisting in subjecting a monoazo dyestuff formed by coupling a diazotized aminosulphonic acid compound of the benzene and naphthalene series with resorcin to air as oxidizing agent in presence of ammonia and iron.

In witness whereof I have hereunto signed my name this 3rd day of February, 1932.
